UNITED STATES PATENT OFFICE.

ANTHONY VANDERVELD, OF GRAND RAPIDS, MICHIGAN, ASSIGNOR OF ONE-HALF TO
HARRY B. PARRISH, OF GRAND RAPIDS, MICHIGAN.

PEDESTAL MOUNTING.

Application filed June 16, 1924, Serial No. 720,183. Renewed December 16, 1927.

This invention relates to a pedestal mount for adjustment thereof to different positions in the length of a horizontal track, and is particularly directed to novel means for automatically holding the pedestal in any position to which it is moved along the track, such means being readily disengaged whenever desired so as to free the pedestal that it may be moved to another desired position. 10 The pedestal in question is designed to support a measuring or measuring and computing machine used in the sale of cloth and ribbon or like goods, the track being mounted horizontally at the rear of the counter and the pedestal with the machine which it carries being adapted to be moved to different positions in the length of the counter as may be desired many times in handling the goods sold. The track is of channel 15 form, substantially, with downturned and upturned lips at the free edge portions of the flanges whereby a guideway is formed to receive co-acting portions on the pedestal. In the formation of the track it is practically impossible to make each and every track absolutely uniform through the desired length and in installing the track it is many times slightly bent or otherwise malformed so that if a pedestal is formed at 20 its lower end at the factory to snugly engage with a specified track it may not operate properly with the track after installation; and in any event each track and pedestal must be fitted together to be sure that 25 the same will work properly, the pedestals and tracks not being interchangeable. With my invention these disadvantages are eliminated the tracks and pedestals in a large quantity of tracks and pedestals being interchangeable and the construction applied 30 to the pedestal being self-corrective of any minor discrepancies or differences in the track formation and of any minor malfunction such as may occur in the installation 35 of the track on the counter.

The construction by means of which the above ends are attained is illustrated in the accompanying drawing in which,

Fig. 1 is an elevation of a fragmentary portion of a track with the pedestal in operative connection therewith.

Fig. 2 is an enlarged horizontal section through the pedestal and track, the section being taken between the upper and lower

guide lips of the track and looking in a 55 downward direction, and

Fig. 3 is a fragmentary enlarged side elevation of the lower part of the pedestal, the track being shown in transverse vertical section.

Like reference characters refer to like parts in the different views of the drawing.

The track 1 is of a channel form with the upper and lower flanges formed with a downturned lip 2 and an upturned lip 3, 65 respectively, at their free edges, the lips extending toward each other as shown. This track is designed to be secured to the rear edge of a counter top by screws which may pass through the web of the track 1 and, 70 in addition, at each end of the track a fitting 4 may be secured with an opening 5 through which a screw may pass into the counter. This fitting is provided also with a projection 4^a which fits into the end of the track 75 closing the same and serving as a stop to prevent disengagement of the pedestal from the track after the installation on the counter has been completed.

The measuring or measuring and computing machine 6 is supported on a table 7 at the upper end of a post 8 which passes downwardly through and is vertically adjustable in a vertical sleeve 9. The mechanism for accomplishing the vertical adjustment of the post 8 is not shown in the present case, being the subject matter of a separate application for patent. At the lower end of the post 9 oppositely extending integral arms 10 and 11 are formed at their ends having portions 10^a and 11^a respectively which enter into the track between the upper and lower guide lips 2 and 3. The arm 11 in its vertical side is provided with an elongated opening 12 as shown for a purpose to be later described. A tongue 13 is cast with and projects downwardly from each of the arms 10 and 11 near their outer ends entering the groove between the lower guide lip 3 and the web of the track as best shown in Fig. 3. Also a tongue 14 is cast integral with the arms substantially at their mid portions and at the upper side thereof, extending upwardly into the groove between the upper guide lip 2 and the web of the track 1. The pedestal is thus mounted for sliding movement lengthwise of the track and in practice the space for the recep-

100
105

tion of the tongues 13 and 14 is sufficient that said tongues are loosely received therein in sufficient tolerance being provided that the ordinary discrepancies incidental to manufacture in the different tracks are more than compensated for and also slight malformation of the track such as may occur by setting the attaching screws too tightly or otherwise will have no effect on the free movement of the pedestal lengthwise of the track when it is free to do so.

At the lower end of the sleeve 9 on the inner side thereof in the open space between the upper and lower sides of the arms 10 and 11, a boss 15 is cast integral with the sleeve extending toward the web of the track and being machined on its face at an angle to the length of the track web as indicated at 16 in Fig. 2. A bar of flat metal 17 is located 20 between the boss and the inner side of the web of the track, at one end being turned at right angles to make a handle 18 which extends outwardly through the opening 12 heretofore described, and between its ends 25 being formed with an off-set intermediate portion 19 the face of which contacting with the face 16 of the boss 15 lies at the same angle as said face 16. A spring 20 is secured at one end to the bar 17 at the bend thereof where handle 18 joins and at its other end is connected with a pin 21 permanently secured to the arm 11 as shown in Fig. 2. This spring under tension normally moves the bar 17 lengthwise so as to tend 30 to bind the section 19 against the face 16 thereby forcing the tongues 13 and 14 against the guide lips 2 and 3 while the bar 17 bears against the inner side of the web of the track. This serves to hold the pedestal against movement thereof along the track and also prevents any oscillation of the pedestal in a direction transverse of the track.

When it is desired to move the pedestal 45 the sleeve 9 is grasped by the hand and a finger brought against the handle 18 to move bar 17 lengthwise against the tension of spring 20. This disengages the section 19 from the boss 15 and frees the pedestal for movement. As soon as it has been moved 50 to a desired position the handle 18 is released whereupon the spring 20 again draws the bar 17 to locking position and the pedestal is automatically held in the position to 55 which it has been moved.

The construction described is simple and particularly practical for the attainment of the ends for which it is designed. The invention is defined in the appended claims 60 and is to be considered comprehensive of all forms of structure coming within their scope.

I claim:

1. In combination, an elongated track including a vertical web, upper and lower

flanges and downwardly and upwardly turned lips at the edges of the flanges paralleling the web, a pedestal including a vertical member located adjacent the track and formed with oppositely extending horizontal arms and a boss projecting toward the web from said vertical member, said boss having its free end face located at an angle to the length of the web, means on the arms loosely engaging in the grooves between said lips and web of the track, and a manually operable member located between the boss and web and having a section to engage the boss with the side thereof engaging the boss in a plane substantially paralleling the said 80 face of the boss, said member being spring operated to normally draw said section of the member into engagement with the boss.

2. In combination, an elongated track including a vertical web, upper and lower flanges and downwardly and upwardly turned lips at the ends of the flanges paralleling the web, a pedestal including a vertical member formed with oppositely extending horizontal arms located adjacent the track, tongues on the arms loosely engaging in the grooves between the web and lips of said track for free sliding movement of the pedestal on the track, means carried by the pedestal spring operated to normally hold the pedestal against accidental movement along the track and prevent oscillation of the pedestal in a vertical plane with respect to the track, and means extending outwardly from one of said arms of the pedestal for manually operating said last mentioned means to release the pedestal for free movement along the track.

3. In combination, an elongated track, a pedestal mounted for free sliding movement along the track, interengaging means between the track and pedestal carried by the pedestal for wedging the pedestal into secure engagement with the track, and means extending outwardly from said last mentioned means through an opening in the pedestal for manually operating said means to free the pedestal for movement along the track.

4. In combination, an elongated track, a pedestal mounted to traverse the track, a member carried by the pedestal adapted to be interposed between the pedestal and track and hold the pedestal against movement with respect to the track, a spring normally acting on said member to move the same to operative position, and a handle to said member for manual operation to move said member to inoperative position.

5. In combination, an elongated horizontal track, a pedestal positioned vertically adjacent the track, means for slidably mounting the pedestal on the track, a member carried by the pedestal and movable to different positions, in one of which it wedges

between the pedestal and track and in another it frees the pedestal for movement along the track.

6. In combination, an elongated horizontal track, a pedestal positioned vertically adjacent the track, interengaging means between the pedestal and track for slidably mounting the pedestal to traverse the track, a member movable with the pedestal and disposed between the said pedestal and track, spring means tending to draw the said member in one direction, said member when drawn in such direction wedging between the pedestal and track, and a handle portion connected with the member and extending outwardly in position to be manually operated to move the member in the opposite direction against the spring means.

7. In combination, an elongated track positioned horizontally and including a vertical web, upper and lower flanges and downwardly and upwardly turned lips on the flanges paralleling the web, a pedestal including a vertical member located adjacent

the track and formed with oppositely extending horizontal arms and a boss projecting toward the web from said vertical member, said boss, at its free end having a face located at an angle to the length of the web, interengaging means on said arms for engaging in the grooves between said lips and web to mount the pedestal on the track for free sliding movements lengthwise thereof, a flat bar located between said boss and web and formed with an intermediate section located in a plane paralleling the face of the boss, said bar at one end having a handle portion turned at right angles and extending outwardly through one of said arms, said arm being formed with an elongated opening to pass the handle portion, and a spring connected to the bar and pedestal tending to force said intermediate section of the bar into engagement with the said face of the boss.

In testimony whereof I affix my signature.

ANTHONY VANDERVELD.
